UNITED STATES PATENT OFFICE

2,545,914

AGITATOR

Henry F. Boucher, Spencer, Mass.

Application June 11, 1948, Serial No. 32,411

6 Claims. (Cl. 95—89)

1

This invention relates to new and useful improvements in agitators and the primary object of the present invention is to provide an apparatus applicable for use in holding and agitating photographic film until the same has been properly processed in a developing bath or solution.

Another important object of the present invention is to provide an oscillating shaft, a rotary shaft, and embodying novel and improved means connecting the rotary shaft to the oscillating shaft for transmitting torque from the rotary shaft to oscillatory motion of said oscillating shaft, thus agitating a film supported relative to the oscillating shaft in a developing solution.

A further object of the present invention is to provide an oscillating shaft, and novel and improved support means movable with the oscillating shaft and adjustable to support rolls of film of various sizes.

A still further aim of the present invention is to provide an agitator for use in the treating of photographic film, that is small and compact in structure, simple and practical in construction, neat and attractive in appearance, efficient and durable in operation, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which—

Figure 1 is a perspective view of the present film agitator, and with parts thereof broken away and shown in section for the convenience of explanation;

Figure 2 is a longitudinal vertical sectional view taken substantially through the center of Figure 1;

Figure 3 is a bottom plan view of the present invention, the housing floor removed therefrom;

Figure 4 is a longitudinal horizontal sectional view taken substantially on the plane of section line 4—4 of Figure 2, and;

Figure 5 is a fragmentary bottom plan view of the adjustable support plate used in conjunction with the present invention.

Referring now to the drawings in detail, wherein for the purpose of illustration, there is disclosed a preferred embodiment of the present invention, the numeral 10 represents a housing or casing of any suitable material generally, having an integral chamber 12 of preferably cylindrical shape, the bottom wall 14 of which is spaced above the lower wall 16 of the housing 10.

2

The lower wall 16 of the said housing 10 is provided with a substantially rectangular opening 18 that is closed by a removable floor or plate 20. This floor 20 being removably secured to corner posts or ribs 22 depending from the bottom wall 14 by suitable fasteners (not shown) whereby the lower face of the floor 20 will be co-planar with the lower face of the lower wall 16, thus permitting both the floor and wall 16 to engage a supporting structural element or bearing surface.

The housing 10 is also provided with a removable end wall 24, so that an electric motor 26 may be mounted in a compartment 28 adjacent the chamber 12. A gear box or casing 30 is supported within the compartment 28, and is connected to the drive shaft of motor 26, whereby the outwardly, depending driving shaft 32 that projects from the gear box 30 will be rotated at a lower rate of speed than the drive shaft of the motor. (This reduction gearing 30 is of a known type and therefore is not shown.)

Rotatably supported in a bearing 34 carried by the central portion of the bottom wall 14, is a substantially vertical driven or oscillatory shaft 36 that is embraced by an axial tube or sleeve 38 that forms an integral part of the wall 14. The upper end of the tube 38 supports a further bearing 40 for the shaft 36. A stop collar carried by the upper terminal of the shaft 36 bears upon the bearing 40 to prevent downward sliding movement or longitudinal movement of the shaft 36 relative to the tube 38.

An outer sleeve or tubular support 44 loosely embraces the tube 38, and is formed at its lower end with a base plate 46 the outer edge or edges of which are spaced from the walls of the chamber 12. The upper terminal of the outer sleeve 44 is integrally formed with a closure plug or cap 48 having a reduced annular extremity 50 that engages a bearing 52 carried by a socket 54 which is integrally formed with the central portion of a closure plate 56.

The closure plate 56 is provided with a peripheral rib or flange 58 having a recess 60 that engages the flanged portion 62 of the housing 10.

Substantially V-shaped latches or holding members 64 of resilient material are secured at one of their ends to the flange 58 of the closure 56, and these latches engage the lower face of the flanged portion 62 to retain the closure plate 56 relative to the upper open end of the chamber 12.

Removably secured to the lower face of wall 14, is a plurality of guides 66 that slidably engage a rack bar 68 having a toothed longitudinal edge 70. This rack bar 68 is spaced relative to

and parallel to a further rack bar 72 by a rigid spacer strip or arm 74.

The lower face of the rack bar 72 bears upon the inner or upper face of the floor 26, and the toothed longitudinal edge 76 thereof engages the arcuately disposed teeth 78 of a wheel or gear 80 that is removably secured to the lower terminal of shaft 36, and between the wall 14 and floor 26.

Secured by any suitable means to the driving shaft 32, is an annular plate or disc 82 that supports an eccentrically disposed pin 84, that is spaced relative to the driving shaft 32. This pin 84 slidably and pivotally engages a longitudinal slot 86 provided at one end of an actuating arm 88.

Integrally formed with the arm 88, is a segmental or arcuate plate 90 having an arcuately toothed edge 92 that engages the teeth 92 of the rack bar 66. A pivot pin 94 secures the plate 90 to the bottom wall 14.

An upper plate 96 is provided with a central opening that slidably engages the sleeve 44, and integrally formed with or rigidly attached to the plate 96, is a collar 98 of resilient material having circumferentially spaced, longitudinal slots 100 and circumferentially spaced arcuate fingers 102 that selectively engage one of a plurality of longitudinally spaced grooves or recesses 104 provided in the sleeve 44 for adjustment of the plate 96 relative to the plate 46.

Integrally formed with the inner walls of the chamber 12, is a plurality of substantially vertical ribs 106 for a purpose which will later be more fully apparent.

A switch 108 is applied to the housing 10 and controls the motor 26, so that the said motor may be started or stopped when desirable.

Rigidly attached to or forming an integral part of the housing 10, is a basin or trough 110 that is connected to the chamber 12 by a passage 112, whereby a solution may be placed into the chamber 12 without the necessity of having to remove the closure plate 56.

In practical use of the present invention, when the switch is actuated to an "on" position, the driving shaft 32 will be rotated and likewise the disc 82 will be rotated. Since the arm 88 is pivotally and slidably connected to an eccentrically mounted pin 84 carried by the disc 82, the said arm 88 will reciprocate or oscillate about pin 94 causing a swinging or oscillating motion to be imparted to the plate 90. Since the toothed edge 92 of the plate 90 engages the toothed edge 70 of the rack bar 68, as the said plate 90 is oscillated, both rack bars 68 and 72 will be reciprocated, in a back and forth motion, to effect an oscillating motion of the shaft 36.

A roll of film is wound about the sleeve or spool 44 so that the lower edge of the film will bear upon the plate 46, and the plate 96 is adjusted so that the same will bear upon the upper edge of the film, thus preventing movement of the said film relative to the sleeve 44. As the cap 50 of the sleeve 44 is provided with a substantially square recess 114 that engages the squared terminal 116 of the shaft 36, the said sleeve 44 will likewise be oscillated during the oscillation of the shaft 36.

The ribs 106 provided on the inner walls of the chamber 12, will further engage the film to agitate the same as the said sleeve 44 is being oscillated, and further, the ribs 106 will limit the movement of the film relative to the sleeve 44.

Although there is shown in the drawings, an electric motor 26 which will rotate the disc 82,

it is apparent that any such power means may be employed for rotating the disc 82.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and the scope of the appended claims.

Having described the invention, what is claimed as new is:

1. An agitator for film comprising a frame, a driving shaft carried by the frame, a reciprocating member mounted on said frame and including first and second unitary acting rack bars, guides carried by said frame slidably receiving the first rack bar, a wall underlying said member and slidably supporting the second rack bar, a gear on said shaft engaging said second rack bar, and means engaging said first rack bar for reciprocating said rack bars as a unit.

2. An agitator for film comprising a housing having a false bottom, a solution chamber and a motor compartment, a tube permanently fixed to and rising from the bottom wall of said chamber, a shaft positioned in said tube for rotation and having a lower end received in said false bottom, means mounted within said false bottom and connected to the lower end of said shaft for imparting oscillatory motion to said shaft, a motor mounted in said compartment and connected to said shaft oscillating means for operating the latter, and film supporting means rotatable with the shaft and located within the chamber.

3. An agitator for film comprising a housing having a false bottom, a solution chamber and a motor compartment, a tube attached to and rising from the bottom wall of the chamber, a film holder supported for rotation on said tube and positioned in said chamber, an oscillatable shaft within said tube and having a lower end extending through the bottom wall of said chamber to enter the false bottom, means within said false bottom for oscillating said shaft, and power means within the compartment and operatively connected to said shaft oscillating means, said shaft being connected to said holder for oscillation of said holder in response to oscillation of said shaft.

4. An agitator for film comprising a housing having a false bottom, a solution chamber and a motor compartment, a tube attached to and rising from the bottom wall of the chamber, a film holder supported for rotation on said tube and positioned in said chamber, an oscillatable shaft within said tube and having a lower end extending through the bottom wall of said chamber to enter the false bottom, means within said false bottom for oscillating said shaft, power means within said compartment and operatively connected to said shaft oscillating means for operating the latter, said shaft being connected to said holder for oscillation of said holder and said shaft as a unit, and means mounted within said chamber for engaging and agitating film supported on said holder during oscillation of said holder.

5. The combination of claim 4 wherein said agitating means includes a plurality of vertical ribs on the inner walls of said chamber.

6. An agitator for film comprising a housing having a false bottom, a solution chamber and a motor compartment, a tube attached to and rising from the bottom wall of the chamber, a film holder supported for rotation on said tube and positioned in said chamber, an oscillatable shaft within said tube and having a lower end extending through the bottom wall of said chamber to enter the false bottom, means within said false bottom for oscillating said shaft, power means within said compartment and operatively connected to said shaft oscillating means for operating the latter, said shaft being connected to said holder for oscillation of said holder and said shaft as a unit, and means mounted within said chamber for engaging and agitating film supported on said holder during oscillation of said holder, said agitating means including a plurality of vertical ribs on the inner walls of the chamber, said holder including upper and lower 20

horizontal plates, said chamber including a cylindrical wall, said ribs being circumferentially spaced and said plates being circular and of a diameter considerably less than the diameter of said chamber to permit the plates to oscillate past said ribs without engaging said ribs.
